[57] CLAIM

The ornamental design for a set-top-box, as shown and described.

DESCRIPTION

FIG. 1 is a perspective view of a set-top-box showing our new design;

FIG. 2 is a top plan view thereof;

FIG. 3 is a front elevational view thereof;

FIG. 4 is a left side elevational view thereof; and,

FIG. 5 is a right side elevational view thereof.

The broken line showing of the rear portion of the set-top-box on FIGS. 1-2 and 4-5 is for illustrative purposes only and forms no part of the claimed design.
